ROTARY REPRODUCING COPYING OR PRINTING MACHINE.

1,124,725.

Specification of Letters Patent.

Patented Jan. 12, 1915.

Application filed March 8, 1913. Serial No. 753,042.

To all whom it may concern:

Be it known that we, EMIL GLAS and BERNHARD SOKAL, subjects of the Emperor of Austria-Hungary, residing at Vienna, in the Empire of Austria-Hungary, have invented certain new and useful Improvements in and Relating to Rotary Reproducing Copying or Printing Machines, of which the following is a specification, reference 10 being had therein to the accompanying drawing.

The present invention has for its object a device which serves to supply printing ink to the inner side of the rotary drums of reproducing machines and which is characterized by the fact that the ink is supplied by means of an inking roller which, owing to the rotary movements imparted to the drum is alternately applied to a rotating ink roller and to the inner side of the rotating drum.

In order to adapt the angular magnitude of the portion of the inner periphery of the printing roller traversed by the inking roller 25 to the length of the printing roller segment occupied by the text to be reproduced, adjustable control members are provided, by the adjustment of which the application and the removal of the inking roller takes place 30 along those generating lines of the printing roller that limit the portions utilized for the time being: by this means the useless inking of the surfaces of the printing roller that are not for the time being in use is 35 avoided.

Additional improvements relate: to the mounting of the inking roller, by means of which the intimacy of its contact with the ink roller can be modified: to a device for 40 automatically setting the inking roller parallel, on the one hand with the ink roller or the inner surface of the printing roller on the other hand and finally to a device by means of which toward the end of the 45 printing the inking of the inking roller can be stopped so that notwithstanding the further actuation of the apparatus it takes no fresh ink from the ink roller.

Figures 1 and 2 of the accompanying 50 drawing illustrate a device embodying the invention in cross section and in longitudinal elevation partly in section, Fig. 3 is a view similar to Fig. 1 in which, however,

the inking roller is not in contact with the ink roller as in Fig. 1 but with the inner 55 face of the printing roller. Fig. 4 shows the apparatus in side elevation viewed from the right in Fig. 2. Fig. 5 illustrates diagrammatically the arrangement of the cams producing the oscillating movement of the inking 60 roller; the sector faces of the cams which form part of the same cylindrical surface, have been shown in this figure for the sake of clearness as conforming to a different cylindrical surface. Fig. 6 shows the 65 mounting of the inking roller. Fig. 7 is a cross section on the line A A of Fig. 4 to a larger scale. Fig. 8 is a section on the line B B of Fig. 7.

The apparatus is mounted in the usual 70 manner between two uprights *rr* united by distance bolts *z* and the fixed shaft *f* (Figs. 1 to 4), the hubs *v*, *v* of the two plates *p*, *p* are loosely mounted upon the fixed shaft *f*; these plates are connected one with the other 75 by means of a cylindrical surface *m* embracing approximately one half their circumference and forming the printing roller; in the known manner this surface is adapted for the reception of the printing ink and 80 on its outer face for delivering the ink.

Upon the hub *v* located on the left hand in Fig. 2 the handle *z* is mounted; this handle serves in the known manner for rotating the printing roller *m*, *p* while upon the hub 85 *v* located on the right of Fig. 2 a gear wheel 13 is mounted by means of which the shaft 19 of the ink roller *t* which is mounted on the ink trough *h* is actuated. This shaft 90 19, is driven by the intermediary of the gear 90 wheels 13, 17, and before the roller on said shaft comes into contact with the inking roller *a*, it is freed from the ink in excess by means of a scraping or wiping roller *o*. The inner end face of this hub *v* is reinforced 95 by a projecting cam plate 1 comprising approximately 180°; two cams 2, 3 pivotally mounted on the hub *v* are caused to register more or less with this cam plate 1 and they are adapted to be held in any desired position by a clamping screw 4 passing through the hub *v* (Fig. 5). This screw engages the movable cams 2, 3 through slots 5, 6.

The fixed cam 1 and the two cams 2, 3 adjustable and fixable thereon constitute a co- 105 operating cam face which can be enlarged

from 180° up to approximately 300° according to the position of the movable cams 2, 3. The displacement of the cams 2, 3 is produced by means of the pins 16 provided upon the latter and engaging the hub v through arc-shaped slots 15, 16 and showing upon circular scales 18 the total angular magnitude of the cam surface composed of the parts 1, 2, 3.

10 The inking roller (Fig. 6) which rolls alternately upon the ink roller t and on the inner periphery of the printing roller m, p is mounted in a U-shaped frame n which by means of a single pin 7 located at the middle point of its side, is connected with the side of a second frame b which is mounted by means of the pins 8, 8 between the brackets c, c extending downward from the fixed shaft f .

15 20 The downwardly extending sides 9 of the frame b (Fig. 2) are connected one with the other by means of a distance bolt 25 which is embraced at the middle point of its length by a spring 14 fixed to the rigid shaft f , whereby the entire frame system b, n receives the tendency to oscillate in such a manner that the inking roller a reaches the position shown in Fig. 3 in which it contacts with the inner face of the printing 25 roller m, p .

25 30 The oscillation of the frame system b, n and of the inking roller a (Fig. 1) which is opposed by the pull of the spring 14 and owing to which it comes into contact with the ink roller t is produced by means of a two-armed lever d (Figs. 1, 2, 3) which is also mounted between the brackets c , the contact roller 11 of this lever contacting with the cam group 1, 2, 3 already described 35 40 and its downwardly extending arm being connected by a tension rod 10 with the downwardly extending arm 9 of the oscillating frame b .

45 50 In order to insure that the contact of the inking roller a with the ink roller t shall be more or less intimate according to the quantity of the ink and the number of impressions to be made, the arrangement adopted is such that the ends of the brackets c , carrying the frame system b, n mounted in the fixed shaft f form screw spindles 12 and by means of the nuts can be vertically adjusted whereby the vertical position of the bearing trunnions 8 of the roller 55 a experiences a corresponding adjustment (Figs. 1, 2, 3).

60 65 By means of the arrangement already described that the frame n carrying the inking roller a (see Fig. 6) is able to oscillate around the vertical bolt 7 mounted in the frame b the result is attained that the inking roller a is able to bear both upon the printing roller and also upon the ink roller t along its entire length whereby defective taking and delivery of ink are avoided.

In order to stop the inking by the ink roller entirely toward the end of the printing the gear wheel 17 (Figs. 7, 8) is not fast upon the ink roller spindle 19 but is merely connected therewith by means of a 70 dog adapted to be rendered inoperative; this dog of known construction consists of an arm 21 keyed upon the spindle 19 in which a headed driver pin 22 pressed by a spring against the gear wheel 17 is guided; 75 in the pressed in position this pin engages in one of the slotted sectors 20 of the gear wheel 17 and after traversing the sector in question drives the gear wheel 17 this pin being adapted to be lifted out of this sector 20 in opposition to the action of the spring and retained in the lifted position by rotating it, in such a manner that the nipple 30 of the driver pin 22 lifted from the longitudinal slot of the sleeve 23 is 80 placed upon the solid end face of the sleeve 23. In this position of the driver pin 22 the ink roller t will remain at rest and receive no fresh ink even when the printing roller m, p is rotating. 85

90 Before starting to print, in the first place the position of the adjustable cams 2, 3 relatively to the fixed cam 1 is modified in accordance with the number of lines of text to be printed in such a manner that in 95 the case of text comprising approximately only one third of the page, the movable cams 2, 3 are oscillated to the maximum distance from the rigid cam 1, while in the case of a larger number of lines of text the cams 2, 3 are oscillated so far over the fixed cam 1 that the inking roller a remains in contact with the printing roller for the portion of its periphery corresponding to the number of lines. The adjustment of the movable cams 2, 3 necessary for a given number of lines can be read on the scales 18, 18 arranged on the outer end face of the hub v of the roller, the tongues arranged on the adjusting pins 16 of the cams 2, 3 sliding 100 over these scales. 105

110 Normally the apparatus is actuated by means of the handle z the ink roller t being continuously rotated and the inking roller a being alternately applied to the ink roller t and the inner face of the printing roller m, p . Toward the end of the reproduction the ink roller t is brought to rest by raising with the fingers, the headed driver pin 22, whereby the supply of fresh ink to the inking 115 roller a is stopped. 120

Having now particularly described and ascertained the nature of our said invention and in what manner the same is to be performed, we declare that what we claim is: 125

In a rotary reproducing apparatus a hub having a plate, a printing roller on said hub having thereon lines of text to be reproduced, an inking roller adapted to co-operate therewith, a fixed cam on the inner 130

face of said plate, adjustable cams, adjusting pins positioned on said adjustable cams and engaging in slots in said hub plate, and scales on said hub to indicate the adjustment of said cams to vary the time of co-operation of said printing roller and said inking roller, in accordance with the number of lines in the text.

In testimony whereof we affix our signatures in the presence of two witnesses.

EMIL GLAS.
BERNHARD SOKAL.
